M. S. BENTLEY.
MATRIX DRYING PRESS.
APPLICATION FILED FEB. 4, 1908.

921,067.

Patented May 11, 1909.

UNITED STATES PATENT OFFICE.

MARCUS S. BENTLEY, OF LOS ANGELES, CALIFORNIA.

MATRIX-DRYING PRESS.

No. 921,067.

Specification of Letters Patent. Patented May 11, 1909.

Application filed February 4, 1908. Serial No. 414,188.

To all whom it may concern:

Be it known that I, MARCUS S. BENTLEY, a citizen of the United States, residing at Los Angeles, in the county of Los Angeles 5 and State of California, have invented new and useful Improvements in Matrix-Drying Presses, of which the following is a specification.

This invention relates to a drying press 10 for stereotype matrix plates and the prime object thereof is to provide means for quickly and thoroughly exhausting the moisture from the matrix sheets after they have been formed in the usual press.

15 Heretofore matrix drying presses have been utilized in which the matrix sheet is covered with a blanket of some absorbent fabric and the whole placed under pressure and under the action of steam heat. The 20 temperature attained by the steam heat is sufficient to slowly drive the moisture from the matrix into the blanket but there is no means afforded for drying the blanket and the same becomes wet with the moisture 25 from the matrix sheet. This moisture held by the blanket renders it impossible to thoroughly dry the matrix and also increases the time occupied by the drying process to such an extent that it takes longer to merely 30 dry the matrix sheet than it takes for all the remaining operations from the time the form is brought into the stereotype room to the time when the finished stereotype plates are put upon the press.

35 My invention consists of a means to exhaust the moisture from the blankets so that the blankets are kept dry and always in a condition to absorb the moisture from the matrix sheet so that the matrix is dried 40 quickly and thoroughly.

I accomplish the above by means of the device described herein and illustrated in the accompanying drawings, in which:—

Figure 1,— is a perspective view of a matrix drying press embodying my invention, being shown in its open or operative position. Fig. 2,— is a longitudinal section of the same in its operative position. Fig. 3,— is a perspective view of the exhaust plate 45 employed in applying my invention to the usual matrix drying press now in use. Fig. 4,— is an enlarged perspective detail of one corner of the plates shown in Fig. 3. Fig. 5,— is an enlarged sectional detail of the 50 parts shown in operative relation to each other in Fig. 2. Fig. 6,— is a perspective 55 view of another form of exhaust plate. Fig. 7,— is a perspective detail illustrating a typical means employed when the exhaust plate is embodied in the platen of the press. 60 Referring to the drawings 10 designates the base of a matrix drying press of usual construction which is hollow and is provided with inlet and outlet steam pipes 11 by means of which steam under pressure 65 may be admitted to the hollow base to heat the same and any articles which may be placed thereon. This base is preferably supported by legs 12 and is provided with a yoked frame 13 bolted to its upper face 70 which carries a screw threaded spindle 14 at its center having a hand wheel 15' on its upper end and a plate 15 on its lower end. Bolted or otherwise secured to the lower 75 face of plate 15 is an exhaust plate 16 which is provided on its upper surface with a plurality of transverse grooves 17 crossed and connected to each other by a plurality of longitudinal grooves 18 which are slightly larger and deeper than the transverse 80 grooves. A plurality of spaced holes 19 lead from the lower surface of the plate to these grooves, preferably emerging on the sides of the grooves and not in the bottom thereof. The grooves are preferably 85 V-shaped in cross section and the connecting holes or ports, preferably staggered, connect with the grooves on alternate sides of the bottom. By this construction any water of condensation collects in the bottoms of 90 the grooves and cannot pass back through ports 19 but will flow out of grooves 17 into longitudinal grooves 18 which are deeper for this particular purpose. Longitudinal 95 grooves 18 are connected together in any suitable manner as by a groove 20 and an exhaust pipe 21 is connected to both, being connected to any suitable source of exhaust means (not shown). Thus the pressure platen is preferably formed of two 100 members with grooves in the face of one. When the two members are secured together a platen is formed which is provided with interior passages or channels, these channels being connected by ports to the pressure 105 face of the platen. This construction is merely for convenience in manufacture, the principle of the interior channels remaining the same whether the platen is made in this manner or as in the modified form 110 shown in Fig. 7. In this form the channels are formed by holes 30 drilled edgewise

through the platen, ports 19 connecting the pressure face to holes 30. These pass directly to the edge of the platen and exhaust to atmosphere without the aid of any exhaust means. In this regard, exhausting direct to atmosphere, I have shown in Fig. 6 a modified form of bottom plate 16 in which the grooves 17 run directly to one edge without the intervention of any longitudinal grooves as at 18 in Fig. 3. The wet matrix 25 and the type form 26 are placed upon the steam-heated base 10 of the press and a blanket 27 is placed over the same, the exhaust plate being screwed down tightly 15 upon the blanket. The exhaust is then started and the moisture in the matrix is rapidly converted into steam which passes into the blanket and is exhausted therefrom through ports 19 as fast as it is emitted 20 from the matrix. Thus all the moisture is quickly taken from the matrix and the blanket is also kept comparatively dry, forming in this case merely a distributing medium between the matrix and the exhaust 25 plate rather than an absorbent medium as in the usual operation.

Having described my invention what I claim as new and desire to secure by Letters Patent is:—

30 1. In a matrix drying press, a platen provided with a plurality of exhaust passages leading from its pressure face to one of its edges.

2. In a matrix drying press, an interiorly

channeled platen provided with a plurality 35 of exhaust ports connecting the channels with the pressure face of said platen, the channels exhausting to the atmosphere at one of the edges of said platen.

3. In a matrix drying press, a platen provided with a plurality of open ended channels, said channels lying in a plane parallel 40 with the pressure face of said platen, and a plurality of ports connecting said channels with the pressure face of the platen.

4. In a matrix drying press, a heating table, a platen operatively disposed on said table, said platen composed of an upper and a lower member, said lower member provided with a series of channels on its upper 50 face, said channels provided with ports communicating with the pressure face of the platen.

5. In a matrix drying press, a platen provided with channels in its interior, the channels having inclined bottoms, and said platen being further provided with exhaust ports leading from the pressure face of said platen to the inclined sides of the channel bottoms.

In witness that I claim the foregoing I have hereunto subscribed my name this 27th day of January, 1908.

MARCUS S. BENTLEY.
